CONSTRUCTION OF MILK CRATES

Harold S. Lion and Carlisle G. Rohrer, Cincinnati, Ohio, assignors, by mesne assignments, to The Evans Manufacturing Company, Cincinnati, Ohio, a corporation of Ohio

Application October 16, 1934, Serial No. 748,536

13 Claims. (Cl. 217—69)

Our invention relates to the construction of milk crates especially, but not exclusively, of the slatted style, i. e. of the type in which the side and end walls are made up of wooden rails or slats.

5 In such crates it has hitherto been suggested to use inner and outer corner irons between which the slats or rails are engaged. It has also been suggested to provide these corner irons with ears lying between the slats and to fasten the structure together with a wire lacing passing through the slats and through the ears. The lacing has usually been bent over at the bottom, and shoe members have been provided to cover it.

We shall describe our invention in an exemplary embodiment, from a description of which it will be understood that the objects of our invention are the provision of an improved corner construction, and a novel way of fastening the several parts together, which fastening is strong and positive, but easily removed for replacement or repair. It is also an object of our invention to provide a stronger and more serviceable crate.

These and other objects of our invention which will be set forth hereinafter or will be apparent to one skilled in the art upon reading these specifications, we accomplish by that certain construction and arrangement of parts of which we shall describe the aforesaid exemplary embodiment, reference being had to the accompanying drawings, wherein:

Figure 1 is a plan view of a milk crate embodying our invention.

Figure 2 is an elevational view of a corner thereof.

35 Figure 3 is a sectional view taken along the lines 3—3 of Figure 2.

Figure 4 is a perspective view of an outer corner iron.

Figure 5 is a perspective view of an inner corner iron.

Figure 6 is a perspective view of a stacking iron.

Figure 7 shows a tool for removing the locking rods.

45 Figure 7a is an enlarged view of the end of the tool.

Briefly in the practice of our invention we provide inner and outer corner irons in a slatted construction, the corner irons having ears lying between the slats. The slats and the ears have 50 registering perforations, and fastening means are provided in the form of a rod which passes through the registering perforations. The outer corner iron is turned over to form a shoe member, and the rod is removable by means of a tool 55 which is insertable through the perforations in

the shoe member. Locking means are provided for the rod. A new type of stacking iron is likewise intended for use with this combination, and is claimed in a co-pending application entitled Milk crate corner assemblies, filed of even date 5 herewith.

The general assembly of an exemplary crate is shown in Figure 1, where the sides are indicated at 1 and the ends at 2. Longitudinal bottom forming rods are shown at 3, and longitudinal 10 and transverse partition forming rods at 4 and 5. Bottom strut members are shown at 6, and arms 7 connect the partition rods at their crossing points and have an operative relationship with the bottom structure. The interior rodded or 15 other construction of the crate, however, has no necessary bearing upon our invention, and will not be further described.

Reference to Figures 2 and 3 will show that the sides and ends of our crate are formed of slats 1a etc. and 2a etc. respectively. Inner and outer corner irons are shown at 8 and 9. A stacking iron is shown at 10. The inner and outer corner iron members are of generally rectangular cross section, and will be described in some detail. 20

The outer corner iron 9 has portions bent over at the top as shown at 11. Ears 12 are bent up normal to the side walls of the corner iron at intervals. These ears are perforated for a purpose hereinafter to be described, and are intended to cooperate with the ears on the inner corner iron to lie above, below and between each pair of slats or rails in the sides and ends of the box and to act as spacers therefor. The bottom portions of the outer corner iron are bent over to form bottom shoe members 13 and then are continued upwardly to form interspaced members 14 which terminate in perforated, bent over ears 15. The portions of the side walls of both corner irons between the ears are preferably beveled as at 16 40 excepting at the top, as shown. 30

The inner corner iron is likewise of angular formation, having top ears 17, and other ears 18 interspaced therefrom. Whereas in the outer corner iron the ears are bent over inwardly, in 45 the inner corner iron they are bent over outwardly, so that when the irons are assembled with the ends of the slats or rails therebetween the ears and the perforations therein may be aligned with each other and with perforations in 50 the slats or rails. By reason of the portions 14 of the outer corner iron, the inner corner iron does not need to be as long.

In one embodiment of our invention, we form a stacking iron as a separate piece. This is a 55

member of generally angular cross section having a body (Figure 6) and a stacking extension 20. This extension is reduced, and offset from the body, and is of the usual shape to permit its engagement within the bottom shoes of an overlying crate when the crates are stacked. Upper and lower ears 21 and 22 are struck up outwardly from the body of the stacking iron, and are perforated. They are of a size and shape adapted 10 to permit their alignment with the ears on the inner and outer corner irons as clearly shown in Figures 2 and 3. Both the corner and the stacking irons are preferably formed as sheet metal stampings, galvanized or otherwise protected 15 from corrosion.

In assembling the crate the slats or rails go between the inner and outer corner irons. The ends of the upper rails are notched out as at 23 to bring the top ears of the corner irons substantially into the plane of the top of the crate. The lower rails or slats are also notched out as at 24 to bring the shoe portions 13 of the outer corner irons to the level of the bottom of the crate, and further, to accommodate the offset end of a shoe strip 25 which underlies each bottom rail and which may be riveted thereto, as at 26. The stacking irons are added to the assembly with their ears in alignment with the ears of the outer and inner corner irons. When the parts have been put together in this way, assemblies of ears underlie and overlie each rail or slat, and act as supports and as ultimate spacers therefor. Perforations in the several metal members and in the slats or rails are brought into alignment, and the crate may be fastened together with rod means to be described hereinafter.

The perforations in the top rails or slats are somewhat larger than the perforations in the other rails, and also have still further enlarged portions indicated at 26. Rod members 27, which are preferably long enough to extend from the top almost to the bottom of the crate, but are in no event longer than the crate is high, are provided with heads 28, and crooks or shoulders 29. These rod members may be driven through the aligned perforations to complete the crate. When they are so driven, the crook 29 in the rods compresses as it passes through the perforation in the top rails, but expands into the enlargement 26 of the perforation locking the rods against dislodgment. The rods may otherwise be expanded, or other suitable locking means provided. The crate, or any corner portion thereof, however, is easily disassembled for repair or replacement either of a corner iron, a stacking iron, or the rails themselves, by merely driving out the rods 27 until the locking means have come above the upper ears or have otherwise been disengaged. This is conveniently done by means of a tool such as that shown in Figure 7, having a handle and driving head 30, and a shank 31 of about the same size as the rod. The upper end of the shank is preferably hollowed as shown at 31a in Figure 7a so as to provide a positive engagement with the end of the rod. The shank of this tool is inserted through the perforations in the shoe members of the corner irons, and when it contacts the end of the rod, is tapped with a hammer until the rod has been driven far enough out to free the crook therein as aforesaid. After this the rod may be easily withdrawn by the fingers for the remainder of the way. When a new part has replaced the old, the crate is reassembled by reinsertion of the rod. There will, as shown, be two 75 of the rods at each corner of the crate.

It will be understood that modifications may be made in our invention without departing from the spirit thereof.

Having thus described our invention, what we claim as new and desire to secure by Letters 5 Patent is:

1. In combination in a crate, a corner reinforcement member, slats forming a wall of said crate, ears on said member entering in between said slats, a continuous perforation extending 10 through said ears and said slats, a rod in said continuous perforation extending substantially the full length thereof, and releasable means for holding said rod in said perforation, said means comprising a crook in said rod and a cooperating 15 abutment in said perforation.

2. In combination in a crate, a corner reinforcement member, slats forming a wall of said crate, ears on said member entering in between said slats, a continuous perforation extending 20 through said ears and said slats, a rod in said continuous perforation extending substantially the full length thereof, and releasable means for holding said rod in said perforation, said means comprising a sidewise extending abutment in 25 said rod and a cooperating abutment in said perforation.

3. An outer corner iron for slatted crates consisting of an angular body, ears at intervals therealong at both edges to lie between adjacent slats, 30 and bottom portions of said iron bent over to act as shoes, said ears and shoes being perforated, said bottom portions being continued up inside said body for at least the width of one slat and interspaced from said body the thickness of the 35 end of a slat.

4. An outer corner iron for slatted crates consisting of an angular body, ears at intervals therealong at both edges to lie between adjacent slats, 40 and bottom portions of said iron bent over to act as shoes, said ears and shoes being perforated, said bottom portions being continued up inside said body for at least the width of one slat and interspaced from said body the thickness of the 45 end of a slat, and inwardly extending ears on the said continuations of said body, said ears having perforations in alignment with said first mentioned perforations.

5. In combination in a slatted crate, a corner reinforcement member of angular shape having 50 ears adapted to lie between the slats, bottom portions of said member being bent over inwardly so as to enclose the ends of the bottom slats, at least, upon three sides, slats forming a side and end wall of a crate, continuous perforations extending through said ears, said slats and said bottom portions, and fastening means in said continuous perforations extending substantially the full length thereof.

6. In combination in a slatted crate, a corner reinforcement member of angular shape having 60 ears adapted to lie between the slats, bottom portions of said member being bent over inwardly so as to enclose the ends of the bottom slats, at least, upon three sides, slats forming a side and end 65 wall of a crate, continuous perforations extending through said ears, said slats and said bottom portions, rods in said continuous perforations extending substantially the full length thereof, and releasable means for holding said rods in said 70 perforations.

7. In combination in a slatted crate, a corner reinforcement member of angular shape having ears adapted to lie between the slats, bottom portions of said member being bent over inwardly so 75

as to enclose the ends of the bottom slats, at least, upon three sides, slats forming a side and end wall of a crate, continuous perforations extending through said ears, said slats and said bottom portions, and rods in said continuous perforations extending substantially the full length thereof, said means comprising sidewise extending abutments in said rods and cooperating abutments in said perforations.

8. In combination in a slatted crate, inner and outer corner irons having cooperating pairs of ears adapted to lie between the slats, slats forming side and end walls of a crate, continuous perforations extending through said slats and ears, and stiff rods in said continuous perforations extending nearly but not entirely the full length thereof, and means for holding said parts in assembled relation, said means comprising sidewise extending abutments in said rods and cooperating abutments in said perforations.

9. In combination in a crate, a corner angle iron, slats formed a wall of said crate, ears on said angle iron entering between said slats, aligned perforations forming a continuous hole extending through the entire length of said ears and said slats, a rod in said hole of a length sufficient to hold the parts in assembled relation, readily releasable securing means for holding the parts together, said means comprising retaining means within the limits of said hole cooperating with engaging means on said rod.

10. In combination in a crate comprising super-

imposed slats forming the walls of said crate, a corner angle iron having ears located at the top and bottom thereof confining the assembled slats therebetween, said slats and ears having aligned openings therethrough for receiving a readily releasable securing rod thereon.

11. In combination in a crate comprising superimposed slats forming the walls of said crate, a corner angle iron having ears located at the top and bottom thereof confining the assembled slats therebetween, and having other ears entering in between said slats, said slats and ears having aligned openings therethrough for receiving a readily releasable securing rod therein.

12. In combination a crate comprising superimposed slats forming the walls of said crate, a corner angle iron having ears located at the bottom thereof confining the assembled slats thereabove, said slats and ears having aligned openings therethrough for receiving a readily releasable headed securing rod therein.

13. In combination a crate comprising superimposed slats forming the walls of said crate, a corner angle iron having ears located at the bottom thereof confining the assembled slats thereabove and other ears entering in between said slats, said slats and ears having aligned openings therethrough for receiving a readily releasable headed securing rod therein.
